UNITED STATES PATENT OFFICE.

WILLIAM A. TIMM, OF BERWYN, ILLINOIS, ASSIGNOR TO WESTERN ELECTRIC COMPANY, INCORPORATED, OF NEW YORK, N. Y., A CORPORATION OF NEW YORK.

CONTAINER FOR INSULATING OR IMPREGNATING COMPOUNDS.

1,386,912.

Specification of Letters Patent.

Patented Aug. 9, 1921.

Application filed July 8, 1918. Serial No. 243,933.

To all whom it may concern:

Be it known that I, WILLIAM A. TIMM, a citizen of the United States, residing at Berwyn, in the county of Cook and State of Illinois, have invented certain new and useful Improvements in Containers for Insulating or Impregnating Compounds, of which the following is a full, clear, concise, and exact description.

10 This invention relates to containers for insulating or impregnating compounds, and more particularly to a portable supply tank for replenishing the supply of insulating or impregnating compound used in connection with machines for treating covered conductors.

In the machines which are used in the treatment of covered conductors it is important that the impregnating compound be maintained at practically a uniform temperature considerably above the ordinary room temperature in order to prevent the compound from forming lumps which adhere to the conductor and prevent the application of the compound in a uniform manner.

It is the object of this invention, therefore, to provide a convenient, safe, and efficient means for replenishing the supply of 30 impregnating or insulating compounds in the tanks without causing the compound to become cold and lumpy.

In accordance with the general features of this invention, there is provided a portable tank in which the impregnating compound can be heated to the desired temperature, thoroughly mixed to dissolve all lumps, and rapidly conveyed to the tanks or containers of the impregnating machine without causing an undue drop in the temperature of the compound in the impregnating machine.

One of the features of this invention relates to the construction of a discharge pipe by means of which the impregnating compound is prevented from cooling or lumping during its passage from the container to the tank which is to be supplied, which feature consists essentially in surrounding the discharge pipe with an electrically operated heating element.

In accordance with another feature of this

invention, the discharge pipe is mounted upon a swivel connection by means of which it may be turned to discharge through a funnel back into the container for the purpose of mixing or stirring the compound within the container. 55

The method of mounting the discharge pipe, pump, and motor in order that they may be readily removed from the container 60 is also believed to be patentable.

A further feature of this invention relates to the provision of means for connecting the heating element with a supply circuit in such a manner that a quick, high heat 65 may be obtained for melting fresh compound; or a lower heat may be provided for maintaining the compound at a uniform temperature.

In the drawings illustrating this invention

Figure 1 is a view in side elevation of a container embodying the features of the invention;

Fig. 2 is a plan view of the parts shown 75 in Fig. 1;

Fig. 3 is a detail perspective view illustrating the removable feature of the pump, motor, and discharge pipe of the container;

Fig. 4 is a cross-sectional view of the discharge pipe illustrating the manner of applying the heating element thereto; 80

Fig. 5 is a cross-sectional view of the container illustrating the construction of the heating element and the method of mounting 85 it in the container, and

Fig. 6 is a diagram of a connection used in connection with this invention.

As shown in the drawings, 5 designates a container supported upon wheels 6-6 and 90 having mounted upon the bottom thereof front and rear supporting wheels 7 and 8. A handle 9 is attached to the side of the container 5 for the purpose of propelling it.

As shown in Fig. 5, the container 5 comprises an outer metal casing member 10 and an inner casing member 11, between which casing members is located a wall 12 of heat insulating material. Located within the chamber formed by the inner walls of the 100 inner casing member 11 is an electrical heating element 13 surrounding a perforated

sheet metal basket 14 supplied with handles 15—15 by means of which the heating element and basket may be removed from the container. The impregnating compound is 5 contained within the same chamber as the heating element and is acted upon thereby.

The interior of the container is made 10 easily accessible through two hinged covers 20 and 21 which, as shown in Fig. 5, are composed of heat resisting walls 22 and 23 surrounded by metal casings 24 and 25. As 15 shown in Fig. 2, the hinged covers 21 and 22 are L-shaped and each is provided with a handle 27 by means of which it may be swung upon its hinges 28.

Removably secured between the narrower portions of the hinged covers 20 and 21 is a platform 30 preferably of heat insulating material. As more clearly shown in Fig. 3, 20 this platform 30 is mounted upon a bracket 31 which is adapted to be secured by means of bolts to one wall of the container, the bolts being provided on one end with wing nuts 33—33 to facilitate the ready removal of this 25 support 30 from the container. Upon a supporting bracket 34 carried by the support 30 is mounted a motor 35 adapted to drive a pump 36 to force the impregnating compound through a discharge pipe 37. Extending 30 through the support 30 is a thermometer 40 by means of which the temperature of the impregnating compound within the container is registered.

The hinged cover 20 is also provided with 35 an opening through which extends a funnel 42. The discharge pipe 37 is mounted upon a swivel joint 43 so that it may be swung with its open end directly over the funnel 42 to pass the impregnating material back 40 into the container. This discharge pipe 37 is surrounded by a heating element 44 incased in a heat insulating compound 45 and having suitable terminals by means of which it may be connected to a source of current supply. An ordinary molasses gate 46 is secured to the open end of the discharge 45 pipe 37.

A ventilating opening 41 is provided in the cover 21 for the escape of gases and 50 fumes.

The pump 36 may be operated by means of the motor 35 or by means of a hand wheel 47 which is adapted to engage with the pumping mechanism through the agency of 55 a clutch 48.

Mounted upon flexible cords carried upon the portable tank are plugs 50, 51, 52, 53, and 54, the plug 50 being connected with conductors which lead to the motor 35 and 60 adapted for insertion into a jack 60, as shown in Fig. 6, which jack is adapted to be connected by means of a switch 56 across the leads of a three-phase power circuit. A second switch 57 is provided for connecting 65 the primary 58 of a transformer across the

power leads of the three-phase circuit. The secondary 59 of this transformer is provided with taps leading to a plurality of switches 62, 63, and 64 by means of which current is supplied to the heating element 70 13 of the container, which heating element is preferably divided into three phases adapted by means of the plugs 52, 53, and 54, jacks 65, 66, and 67, and the switches 62, 63, and 64, to be connected in any desired 75 combination with the windings of the secondary 59. The heating element 44 of the discharge pipe 37 may be connected to one phase of the three-phase circuit through the agency of the switch 68 and a jack 69 which 80 is adapted to be engaged by the plug 51. The conductors attached to the plugs 50 and 51 may be made sufficiently long to extend from the jacks in a power board to any impregnating machine so that the pump may 85 be electrically driven when transferring compound from the portable container to a tank, and the heating element of the discharge pipe may be connected in circuit. Since the amount of compound to be replaced in each tank in a day is very slight, the pump can be operated by the hand wheel, and since it is only necessary to apply heat 90 to the discharge pipe during the stirring or mixing process, the connections are preferably made only when the portable container is not in actual use for replenishing the supply of compound in the tanks. 95

When the compound in the container is brought up to the proper temperature the 100 tank will, due to its construction, retain it at this temperature for a sufficient period of time to permit the replenishment of the tanks without the heating element being energized. 105

The advantages to be gained in the use of the portable container of this invention are that the replenishing compound may be thoroughly stirred or mixed to avoid lumps, the tank could be filled to the proper level in a 110 short period of time thereby preventing the compound already in the tank from cooling to be outside of the required temperature limits, and the compound would be safely transported to the tank and the tank replenished without danger of scalding or burning of attendants. 115

What is claimed is:

1. A portable container for impregnating compound, comprising a heating chamber, an adjustable discharge pipe connected with said chamber, a pump for forcing compound through said pipe, and an opening into said chamber through which the compound may be discharged from said pipe in one position 120 thereof to mix or stir said compound. 125

2. A portable container for impregnating compound, comprising a heating chamber for said compound, a pump, a discharge pipe for withdrawing said compound from said 130

chamber, and a removable support for said pump and said discharge pipe mounted within said container.

3. A portable container for impregnating compound, comprising a heating chamber, a heating element for said chamber divided into a plurality of phases, a multi-phase

power circuit, and means for connecting said heating element with said power circuit in different phase relations to regulate the heating of said compound. 10

In witness whereof I hereunto subscribe my name this 18th day of June, A. D. 1918.

WILLIAM A. TIMM.
